UNITED STATES PATENT OFFICE.

EDWARD H. STAPP, OF KEVIL, KENTUCKY, ASSIGNOR OF ONE-HALF TO ERNEST E. STAPP, OF KEVIL, KENTUCKY.

GRAIN-SCOURING MACHINE.

1,345,273.

Specification of Letters Patent. Patented June 29, 1920.

Application filed June 13, 1916. Serial No. 103,480.

To all whom it may concern:

Be it known that I, EDWARD H. STAPP, a citizen of the United States, residing at Kevil, in the county of Ballard and State 5 of Kentucky, have invented certain new and useful Improvements in Grain - Scouring Machines; and I do hereby declare the following to be a full, clear, and exact description of the invention, such as will enable 10 others skilled in the art to which it appertains to make and use the same.

This invention relates to improvements in grain scouring machines, and has for its primary object to admit of the machine being kept filled to its maximum capacity during 15 the scouring operation.

Another object of the invention is to admit of the major portion of the liberated foreign matter that has been released from 20 the grain being drawn from the machine during the scouring operation, and also admit of any residue, which accompanies the grain during its discharge, being liberated therefrom.

25 A further object of the invention is to provide a novel type of mechanism for regulating the discharge of the grain from the machine.

Other objects will appear and be better 30 understood from that embodiment of my invention of which the following is a specification, reference being had to the accompanying drawings forming a part thereof, in which:

35 Figure 1 is a vertical sectional elevation of the scouring machine and the frame therefor.

Fig. 2 is a vertical sectional view taken through the discharge chamber.

Fig. 3 is a top plan view of one of the 40 scouring blades,

Fig. 4 is a side elevation of the discharge regulating means detached from operative position,

Fig. 5 is a top plan view of the supporting 45 element for the discharge regulating member shown in Fig. 4.

Referring to the drawings in detail, the letter A designates the scouring machine as an entirety, and which machine includes 50 a frame structure 1 having mounted therein, at one side thereof, a cylindrical shaped casing 2. Positioned within the casing 2 is a scouring cylinder 3, which is arranged in spaced relation with the inner surface of 55 the side of the casing 2 and the said scour-

ing cylinder has its side walls perforated, as shown at 4, and the walls of the perforations provided with inward extensions 5, so as to render the inner surface of the scouring cylinder 3 roughened. A vertical 60 shaft 6 passes through the scouring cylinder 3 and has that portion which is disposed within the cylinder 3 squared, and associated with the said squared portion of the shaft 6 is a plurality of superposed rotary 65 scouring blades 7. Each of these scouring blades consists of a pair of segments 8, which are connected with each other by means of a web 9. Alternate scouring blades 7 are arranged in planes intersecting the 70 adjacent scouring blades, and the segments of all of the blades are perforated, as shown at 10, and have projections 11 extending in opposite directions, so as to roughen the upper and lower surfaces of the segments of the scouring blades. Spacing elements 12 are interposed between 75 adjacent scouring blades and hold the same properly spaced. The lower end of the cylinder 3 is formed to provide a discharge 80 spout 13, which projects a distance below the lower end of the casing 2 and is received by a cylindrical sleeve 14, which is adapted to have vertical adjustment on the spout 13 and is carried by a supporting element 85 consisting of an annular collar 15 adapted to engage beneath an annular lip 16 on the upper end of the sleeve 14, and a pair of arms 17 projecting from the sleeve 14, at diametrically opposite points, and have 90 their outer ends overlying opposed horizontally disposed bars 18 carried by the frame 11, the said outer ends of the arms 17 having set screws 19 adjustable therethrough and against the bars 18, so as to effect movement 95 of the arms 17 when turned in either direction. An inclined chute 20 is disposed below the cylinder 3 and has its upper end enlarged, as shown at 21, and located directly below the lower end of the sleeve 14, and has its lower end extending beyond the forward side of the frame 1 and arranged in communication with a discharge chamber 22. The lower end of the shaft 6 extends through 100 the discharge spout 13 and through an opening in the lower wall of the chute 20 and has the terminal thereof journaled in a bearing 23 carried by a cross bar 24, on the frame. A collar 25 is secured to the inner surface 105 of the lower wall of the chute 20 and sur- 110

rounds the adjacent portion of the lower end of the shaft 6, and said collar forms a bearing seat for a collar 26, depending from the lower side of the disk 27, which is carried by the lower end of the shaft 6, the said disk 27 being located in spaced relation to the lower end of the hollow body 14, and a set screw 28 is adjustable through the collar 26 and against the shaft 6 for locking the disk to the shaft so as to effect rotation of the disk when the shaft is rotated.

The upper end of the space between the casing 2 and the scouring cylinder 3 is closed by means of a circular head 29, which has a concentric opening therein through which passes the lower end of an inverted frustoconical shaped hopper 30, the upper end of which communicates with the lower end of a chute 31, which chute conveys grain to the scouring cylinder 3. The upper end of the shaft 6 extends through the hopper 30 and is journaled in a cross bar 32 on the frame 1 and carries a beveled gear 33, which meshes with a bevel gear 34 carried by the adjacent end of a horizontally disposed shaft 35, which shaft is journaled in the frame and has its outer end provided with a pulley 36, which is connected with a suitable source of power supply, not shown.

Suitably mounted within the frame structure, and to one side of the casing 2, is a fan casing 37, having a suction fan 38 therein, mounted on a vertical shaft 39, which extends through the fan casing and has one end journaled in a transverse bar 40 at the lower end of the frame structure 1, and its upper end journaled in a transverse bar 41 at the upper end of the frame structure, and provided with a pulley 42, which has connection with a pulley 43, carried by the upper end of the shaft 6 by means of a belt 44.

The discharge chamber 22 consists of a rectangular shaped hollow body having its lower end opened and having the walls of its upper end pressed inwardly, as shown at 45, and terminally formed to provide a cylindrical portion 46. The rear wall of the chamber 22 is provided with an opening 47, which communicates with the lower end of the chute 20. The upper end of the cylindrical portion 46 has connection with the lower end of a vertical pipe 48, which has its upper end coupled to one end of a horizontally disposed pipe 49, the opposite end of the pipe 49 being connected to the upper end of a vertical pipe 50, the said pipe 50 in turn having its opposite and extending through the top of the fan casing 37 and communicating with the interior of the fan casing.

A vertical pipe 51 has its lower end extending through the top of the fan casing 37 and has its upper end communicating with the lower end of a horizontally dis-

posed pipe 52, the opposite end of the pipe 52 communicating with the space between the scouring cylinder 3 and the casing 2. The casing 2 is provided, at the lower end thereof, and at diametrically opposite points, with air inlets 53 which are adapted to be closed by means of valves 54, slidably mounted on the outer side of the casing 2.

A valve 55 is mounted within the pipe 48 and is adapted, when closed, to cut off communication between the chamber 22 and the fan casing 37.

In use, when the shaft 6 is rotated to impart rotation to the scourers 7 and result in the rotation of the fan 38, the grain within the scouring cylinder 3 will be agitated and moved in contact with the roughened surface of the scouring cylinder and the scouring blades 7, and will have the smut, or other foreign matter, liberated therefrom, the fine matter being drawn through the openings in the side of the scouring cylinder 3 and into the space between the scouring cylinder and the casing, and thence through the pipes 52 and into the fan casing 37 and discharged through an outlet pipe 56 and into a suitable receptacle, not shown. The grain will work downwardly through the scouring cylinder and out through the discharge spout 13 and discharge into the upper end of the chute 20, and thence discharge from the chute 20 through the opening 47 into the chamber 22. The rotation of the fan 29 will cause a suction to be created in the chamber 22, which will draw any of the foreign matter, which accompanies the grain, when it is discharged into the chamber 22, into the fan casing and out through the pipe 56. It will, of course, be understood that the suction created by the fan will not be sufficient to draw particles of grain into the fan casing, the grain being heavier than the matter liberated therefrom.

The cleaned grain is discharged through the lower end of the chamber 22 into a suitable receptacle, to be provided therefor, not shown.

By virtue of employing the slidable cylindrical body 14, the space between the lower end thereof and the disk 27 can be made greater or smaller, so as to regulate the discharge of the grain from the spout 13 to the enlarged portion 21 of the chute 20.

It will, of course, be understood that various minor changes in the details of construction and arrangement of parts may be made without departing from the spirit of the invention as claimed.

Having thus described my invention what I claim as new is:

A grain scouring machine comprising a casing having closed upper and lower ends and provided with air inlets positioned adjacent its lower end, a perforated scouring

- cylinder positioned in the casing and extending through the upper and lower ends thereof, a chute positioned to receive scoured grain from the lower end of the cylinder,
5 a vertically disposed open ended spout having the chute communicating therewith at a point intermediate the height of the spout, grain scourers positioned in said cylinder, a fan housing, a rotatable shaft extending vertically through the fan housing, a fan carried by the shaft within the housing, a dust
- 10 pipe extending from the casing adjacent its upper end and communicating with said fan housing, and a dust pipe leading from the upper end of said spout and communicating with the upper portion of said fan housing. 15

In testimony whereof I affix my signature in presence of two witnesses.

EDWARD H. STAPP.
